Primary Examiner — Dominic V Simone(74) Attorney, Agent, or Firm — Morgan, Lewis & Bockius LLP(57) CLAIM

The ornamental design for a single-sole shoe with green outpatch sole, as shown and described.

DESCRIPTION

FIG. 1 is a perspective view of an embodiment of our new design of a single-sole shoe with green outpatch sole, where the green portions are indicated using the USPTO convention of solid diagonal lines extending from the upper left to the lower right for green;

FIG. 2 is a first side view of the design of FIG. 1;

FIG. 3 is a second side view of the design of FIG. 1;

FIG. 4 is a top view of the design of FIG. 1;

FIG. 5 is a bottom view of the design of FIG. 1;

FIG. 6 is a front view of the design of FIG. 1; and,

FIG. 7 is a back view of the design of FIG. 1.

The broken lines illustrating the front portion of the upper, the half-moon patch, the groove in the outsole, and the heel stripe in the above described Figures are for illustrative purposes only and form no part of the claimed design.
